UNITED STATES PATENT OFFICE.

CARL HERING, OF PHILADELPHIA, PENNSYLVANIA.

APPARATUS FOR AERIAL NAVIGATION.

1,353,955.

Specification of Letters Patent. Patented Sept. 28, 1920.

Application filed October 30, 1915. Serial No. 58,775.

To all whom it may concern:

Be it known that I, CARL HERING, a citizen of the United States, residing in the city of Philadelphia and State of Pennsylvania, have invented certain new and useful Improvements in Apparatus for Aerial Navigation, of which the following is a specification.

My invention relates to apparatus for increasing the buoyancy or lifting or sustaining force of an aeroplane, flying machine, airship, or any similar apparatus navigable through air or water.

My invention resides in a propeller driven aeroplane or other air navigation apparatus having means for applying a lifting or sustaining force resulting from a current or stream of air (other than the current or stream of air caused by the forward motion 20 of the apparatus through air) coöperating with a plane or surface suitably positioned with respect to the air current or stream to produce on the opposite sides of such surface or plane a difference of pressure, the 25 pressure exerted on the under side of the surface or plane exceeding that on the upper side and thereby exerting on the apparatus as a whole a lifting force.

For an understanding of my invention, reference may be had to the accompanying drawing, in which:

Figure 1 illustrates an air nozzle with an associated surface whereby a difference of pressure on opposite sides of the surface 35 is produced.

Fig. 2 is an illustration of a nozzle and an associated surface differently applied with respect to the air current which produces on opposite sides of the surface 40 unequal pressures.

Fig. 3 is a diagrammatic side elevational view of such a lifting surface or plane in coöperative relation with a propeller of an aeroplane.

Fig. 4 is a diagrammatic top plan view 45 of an aeroplane provided with such a lifting surface or plane.

In Fig. 1, N is a nozzle from which issues in a generally horizontal direction a stream or current of air against the under side of the plane or member P constituting a plane curved or inclined with respect to the horizontal air stream. The plane or member P is attached to the nozzle N. The air striking upon the under side of the plane P whose upper side is subjected to substan-

tially the usual atmospheric pressure downward, will produce an excess upward pressure on the under side of the plane P and thereby causing a lifting force in the direction of the arrow a.

In Fig. 2 the member P is attached to the nozzle N beneath the stream or current of air issuing from the nozzle. The blast of air across the upper surface of the member P reduces the atmospheric pressure thereon so that the atmospheric pressure on the lower side of the member P exceeds that on the upper side, with resultant upward force exerted by the air upon the under side of the member P in the direction indicated by the arrow b.

As is well known in the art, an aeroplane or similar apparatus is provided with a propeller which creates a powerful more or less horizontal stream of air resulting from the thrust of the propeller upon the air, which thrust moves the aeroplane forward, the relative movement between the aeroplane and the air in which it is moved causing on the inclined or usual planes or wings of the aeroplane a lifting force sufficient to sustain the aeroplane in the air.

So far as I am aware, however, the blast of air produced by the propeller and moving much more rapidly with respect to the aeroplane than the aeroplane moves with respect to the air in which it is moving forward, has not been availed of to produce a further sustaining or lifting force.

By my invention I employ such blast or current of air produced by the aeroplane propeller without in any way or substantially reducing the thrust of the propeller upon the air body through which the aeroplane is moving.

I employ the blast of air in accordance with the principles illustrated in either Figs. 1 or 2. By preference, however, I employ the principle of Fig. 2, and such application is illustrated in Fig. 3 where R is the propeller rotated at high speed by motor or engine in the usual and well known manner. The blast of air from the propeller R moves from the left toward the right at high velocity above the member P and, as explained in connection with Fig. 2, reduces the atmospheric pressure on the upper surface of the member P with the result that the air pressure on the under side of the member P exceeds that on the upper, with a resultant upward lifting force.

which sustains or assists in sustaining the aeroplane against gravity. The member P may be a true or flat plane, or may be curved, or partially flat and curved as illustrated.

The thrust of the propeller resulting from the production of the air current or blast over the member P serves to drive the aeroplane through the air toward the left in 10 the customary manner, the usual planes or wings of the aeroplane, not shown in Fig. 3, serving as usual to afford a lifting or sustaining force due however to the longitudinal movement of the aeroplane with respect 15 to the air body, the downward and backward inclination or curving of the usual wings giving the usual lifting force.

Fig. 4 is a top plan view of an aeroplane having its usual propeller R and the lateral 20 wings W of a monoplane, biplane or other type. The auxiliary plane P is shown disposed as in Fig. 3 immediately behind and beneath the propeller R so that the stream or current of air in the direction of the 25 arrows produces a lifting force on the under side of the member P.

The velocity of the air current or stream produced by the propeller R with respect to the member P is very high, and much 30 greater than the velocity of the aeroplane as a whole through the air body. The vertical lifting force exerted upon the member P due to the inequality of pressures upon its opposite sides is believed to be proportional 35 to the square of the velocity of the stream of air with respect to the member P. Consequently the lifting force increases rapidly and as the velocity increases and is small at low velocities.

40 The upward lifting force described as exerted upon the member P due to the stream or current of air from the propeller R is relatively a maximum when the motion of translation of the aeroplane through the atmosphere or with respect to the earth is a minimum and decreases as such motion of translation of the aeroplane increases. This means that the additional force available by my invention is the greatest at the time 45 when most needed, namely, in starting from the earth or water or when ascending at a steep angle.

By preference the member P or its equivalent is a member or plane which is added to 50 the usual aeroplane structure and need in no way interfere with the usual function of the propeller, wings or rudders of an aeroplane.

As will be seen from Fig. 3 the downward and backward inclination or curving of the 55 member P, operating as an ordinary wing or plane, produces a lifting force due to the forward movement of the member P through the air caused by the thrust of the propeller R upon the air. In other words the member P may be a wing or plane of an

aeroplane which causes a lifting or sustaining force due to the forward movement of the aeroplane through the air, but which also, due to the positioning of the member P with respect to the propeller R, usefully 70 applies the high velocity of the stream or current of air from the propeller itself in producing an additional sustaining or lifting force.

The lifting force exerted upon the member P in Figs. 2 and 3 is practically nothing when the member P is too far away from the air current or stream, as when it is positioned some distance below the air current or stream, and is practically nothing when 80 inclined or curved too much toward or into the stream or current of air, in which latter case the force may even reverse its direction, as shown in connection with Fig. 1. The position for maximum effect therefore lies 85 between the two positions mentioned.

Where several propellers are used side by side on an aeroplane, each may have associated therewith a member P or its equivalent for producing a lifting force as described. In such case it is preferred that the members P be provided with means for releasing the upward pressure thereon in case one or more of the propellers should stop while in flight, for in such case the 95 member P behind the propeller which has come to rest would discontinue producing the upward lift and if another member P were continuing to produce such lifting force, a turning couple would result which 100 would unbalance the aeroplane. This release of upward pressure upon a member P may be accomplished by forming the surface of the member P by shutter-like slats which may be opened to afford easy air communication from beneath to above the member P. 105

When the member or plane P is applied as an addition to the usual wings or planes of an aeroplane, it should preferably be so positioned with respect to the usual wings 110 or planes that the point through which the resultant lifting force of the usual wings or planes acts and the point through which the lifting force of the member P acts should be approximately vertically over each other, 115 so that when the propeller stops, as in volplaning, and when therefore the lifting force of the member P ceases, the aeroplane will not be thrown too much out of balance.

While the principles herein claimed have 120 been described as to their application to aeroplanes, it will be understood that it is within my invention to apply them to submarines or other devices navigating in water; or to flying fireworks, artificial flying pigeons for target shooting, toy machines, machines for carrying bombs, or any similar devices.

What I claim is:

1. The combination with an aeroplane 130

- comprising a rotary power driven propeller and a wing or plane propelled through the atmosphere by said propeller and located behind said propeller, of an auxiliary plane or wing disposed below and closely adjacent to the air current produced by said propeller, whereby said auxiliary plane or wing exerts a lifting force separate and distinct from lifting force produced by motion 10 of translation of the aeroplane through space.
2. The combination with an aeroplane comprising a rotary power driven propeller and a wing or plane propelled through the atmosphere by said propeller and located behind said propeller, of an auxiliary plane or wing disposed below and closely adjacent to the air current produced by said propeller, whereby said auxiliary plane or wing 15 exerts a lifting force separate and distinct from lifting force produced by motion of translation of the aeroplane through space, the velocity of the air current produced by said propeller with respect to said auxiliary plane or wing exceeding the velocity of the 20 propulsion of the aeroplane through the atmosphere.
3. The combination with an aeroplane comprising a rotary power driven propeller and a wing or plane behind the same and propelled through the atmosphere thereby, of an auxiliary plane or wing disposed below and closely adjacent said propeller and extending rearwardly therefrom, whereby 25 the current of air produced by said propeller reduces the pressure on the upper side of said auxiliary plane or wing and effects a resultant lifting force.
4. The combination with an aeroplane comprising rotary power driven air propelling means and wings or planes propelled through the atmosphere thereby and extending on both sides and to the rear thereof, of an auxiliary plane or wing disposed below and closely adjacent said propelling means and extending rearwardly therefrom, whereby the air current produced by said propeller causes said auxiliary plane or wing to exert a resultant lifting force separate and distinct from lifting force produced by motion of translation of the aeroplane through space.
5. The combination with an aeroplane comprising rotary power-driven air-propelling means and wings or planes propelled through the atmosphere thereby and extending on both sides thereof, of an auxiliary plane or wing disposed below and closely adjacent said propelling means and extending rearwardly therefrom, whereby the air current produced by said propeller causes said auxiliary plane or wing to exert a lifting force separate and distinct from lifting force produced by motion of translation of the aeroplane through space, said auxiliary plane or wing being inclined downwardly toward the rear.
6. The combination with an aeroplane comprising rotary power-driven air-propelling means and a wing or plane propelled through the atmosphere thereby, of an auxiliary plane or wing disposed below and closely adjacent to the air current produced by said propeller, whereby said auxiliary plane or wing exerts a lifting force, the point through which the resultant lifting force of said wing or plane acts and the point through which the lifting force of said auxiliary wing or plane acts being substantially vertically over each other.
7. The combination with an aeroplane comprising power driven rotary air propelling means and wing or plane structure propelled through the air thereby, of auxiliary plane structure disposed below and closely adjacent to the air stream from said means and extending rearwardly and curving downwardly, whereby an auxiliary lifting force is produced.
8. The combination with an aeroplane comprising power driven rotary air propelling means and wing or plane structure disposed to the rear of said means propelled through the air thereby of auxiliary plane structure disposed below and closely adjacent to the air stream from said means and extending rearwardly and curving downwardly, whereby an auxiliary lifting force is produced.
9. An aeroplane comprising power driven rotary air propelling means and wing or plane structure behind said means and propelled through the air thereby, a part of said wing or plane structure disposed below and closely adjacent said air propelling means and inclined downwardly and increasing in width rearwardly therefrom, whereby the excess pressure on the lower surface of said portion of said wing or plane structure produces a resultant lifting force.
10. The combination with an aeroplane comprising power driven rotary air propelling means and wing or plane structure propelled through the air thereby, of means for exerting a lifting force separate and distinct from lifting force produced by motion of said structure through the air comprising wing or plane structure disposed below and closely adjacent said air propelling means and extending rearwardly therefrom, said wing or plane structures overlapping each other longitudinally of the aeroplane.
11. The combination with an aeroplane comprising power driven rotary air propelling means and wing or plane structure behind the same and propelled through the air thereby, of means for exerting a lifting force separate and distinct from lifting force produced by motion of said structure

- through the air comprising wing or plane structure disposed below and closely adjacent said air propelling means and extending rearwardly therefrom, said last 5 named plane or wing structure increasing in width from front to rear.
12. The combination with an aeroplane comprising a rotary power driven propeller and wing or plane structure propelled 10 through the atmosphere by said propeller, of auxiliary plane or wing structure disposed below and closely adjacent to the air current produced by said propeller, whereby said auxiliary plane or wing structure ex- 15 erts a lifting force separate and distinct from the lifting force produced by the motion of translation of the aeroplane through the air and materially in excess of downward pressure produced by said air current 20 from said propeller upon said first named wing or plane structure.
13. An aeroplane comprising the combination with rotary power driven propeller mechanism, of wing or plane structure 25 moved through the air thereby, and an auxiliary lifting plane disposed below the air stream from said mechanism and extending rearwardly therefrom, said plane having an upper surface so shaped and disposed with 30 respect to the air stream that said stream produces a partial vacuum above said surface.
14. An aeroplane comprising rotary power driven propeller mechanism and associated 35 wing or plane structure disposed in such position with respect to the air stream from the propeller mechanism that there is produced adjacent the upper surface of said wing or plane structure a partial vacuum by 40 said stream from said propeller mechanism, whereby there is produced on said wing or plane structure a net lifting force in material excess of all downward forces on said wing or plane structure due to said stream 45 from said propeller mechanism.
15. An aeroplane comprising the combination with rotary power driven propeller mechanism, of wing or plane structure moved through the air thereby, and an auxiliary lifting plane disposed below the air 50 stream from said mechanism and extending rearwardly therefrom, the upper surface of said plane conforming approximately to the form of the under side of said air stream. 55
16. An aeroplane comprising the combination with rotary power driven propeller mechanism, of wing or plane structure moved through the air thereby, and an auxiliary lifting plane disposed below the air stream from said mechanism and extending 60 rearwardly therefrom, the upper surface of said plane situated approximately in but slightly below the surface of separation between the ambient air and the air stream from said mechanism. 65
17. An aeroplane comprising the combination with rotary power driven propeller mechanism, of wing or plane structure moved through the air thereby, and an auxiliary lifting plane disposed below the air 70 stream from said mechanism and extending rearwardly therefrom, said auxiliary plane having such shape that only the air stream from said mechanism passes over its upper surface and only the ambient air passes 75 under its lower surface.
18. An aeroplane comprising a rotary propeller at the front thereof, laterally extending wing structure, and auxiliary lifting plane structure extending rearwardly 80 from said propeller curving downwardly and increasing in width, the upper surface of said auxiliary structure disposed entirely below but closely adjacent to the air stream from said propeller. 85

In testimony whereof I have hereunto affixed my signature this 29th day of October, 1915.

CARL HERING.
